UNITED STATES PATENT OFFICE.

ANDERS ANDERSSON, OF ST. CLOUD, MINNESOTA.

SAW-SHARPENING MACHINE.

SPECIFICATION forming part of Letters Patent No. 748,685, dated January 5, 1904.

Application filed February 5, 1903. Serial No. 142,087. (No model.)

To all whom it may concern:

Be it known that I, ANDERS ANDERSSON, a citizen of the United States, residing at St. Cloud, in the county of Stearns and State of Minnesota, have invented certain new and useful Improvements in Saw-Sharpening Machines, of which the following is a specification.

This invention consists in certain improvements in the construction of machines for sharpening band and other saws, as herein-after fully described in connection with the accompanying drawings, in which—

Figure 1 is a side elevation of a saw-filing machine constructed in accordance with my invention. Fig. 2 is a top plan view of the same. Fig. 3 is an end view of the same, showing the saw and its clamping device. Fig. 4 is a vertical transverse section on the line *y* *y* of Fig. 1 looking in the direction of the arrow thereon. Fig. 5 is a vertical transverse section of the machine on the line *z* *z* of Fig. 1 looking in the direction of the arrow thereon. Fig. 6 is a bottom view of the machine detached from its base-support. Fig. 7 is a vertical transverse section of the machine on the line *x* *x* of Fig. 1 looking in the direction of the arrow thereon. Fig. 8 is a perspective view of the saw-feeding pawl.

30 A is a bed-support upon which the operating-machine is mounted. It may be a tabletop, so as to afford room below it for parts of the mechanism.

B, B', and B² are standards, in which are formed the bearings for the main horizontal shaft C, which carries on one end the bevel-gear c. Meshing with said bevel-gear c is another gear e, mounted upon a vertical shaft E, which receives its power either from the belt-pulley F, if the machine is run by power from a prime mover, or, if run by hand, from a crank G, mounted upon the top of shaft E, said crank having a crank-pin G² and handle G³ thereon. The upper portion of the shaft E has its bearing in a horizontal bar B³, which constitutes a part of the frame and is secured on top of the standards B' B² by bolts b³.

A rod g has one end pivotally connected with the crank-pin G² and its opposite end pivotally connected, by means of a pivoted wrist-pin 2, to the carriage H, which has clamped thereto by means of two hollow

bosses h and i a file I. The carriage consists of a cylindrical sliding rod b, received in suitable bearing-boxes 3, secured in the standards 55 B and B'. Upon the rod b are secured, by means of screw d, the transverse arms 4 and 5 of the carriage. Said arms are united together adjacent to their outer ends by means of a flat bar S, which rests thereon and is secured thereto by screws a. Thus it will be seen that when the shaft E is rotated the carriage H, which is fastened to the sliding rod b, is moved backward and forward by the action of the connecting-rod g, and the saw f 65 is advanced at the proper time, as will hereinafter be explained.

The feeding mechanism of the saw may be described as follows: Mounted on the shaft C, adjacent to the standard B², is a cam J, 7c which bears against an arm or projection k of a transverse rod K, which is movably retained in a way k' through the instrumentality of a lug k² and pin k³, both projecting from the frame of the machine, as shown in 75 Fig. 5. A spring k⁵, bearing against one end of said rod, tends to hold the arm k in engagement with the cam J, and a set-screw k⁶, mounted in the frame at the opposite end of the rod, acts as an adjustment to vary the 80 stroke of the rod in a manner well understood. Said rod K is pivotally connected at its spring-pressed end, as at l, with a rod L, which is in turn pivotally mounted in a collar l', borne upon a thumb-stem l², carried by 85 the standard B'. Said rod L carries loosely at its opposite end a feeding member or pawl M, which, as shown in Fig. 4, terminates in a knife-edge m, adapted for engagement with the teeth of the saw f, the lateral play of said 90 pawl or member M being limited by an arm m', projecting from the standard B. It will thus be observed that as the shaft C is rotated the cam J bears against the arm k of rod K, thereby imparting motion to the shifting rod L and its pawl M, which latter coming in contact with the teeth of the saw f pushes it forward the space of one tooth. During this action the file I is moved to the left to its limit preparatory to acting upon 100 the saw. Said saw is supported near each end by two angle-plates 6 and 7, adjustably secured to the ends of the standards B by thumb-screws 8. To properly clamp the sides

of the saw while the file acts upon it, a cam N is attached to the lower end of the shaft E in a groove formed in the bed-support A, or, if a table is used, it may be simply on the 5 under side of said table. Said cam during the forward motion of the file comes in contact with the laterally-bent end of a reciprocating rod O, which is held in position by the bearing-guide o' at one end and is attached 10 to o to the lower end of the saw-clamp n², which is a lever pivoted at n' to lugs n³, projecting from the side of the standard B, thus tightening the hold of the clamp at the proper time on the saw. In order to increase the 15 cutting power of the file, pressure is brought to bear upon the file-carriage H by means of an angularly-bent lever P, provided at its upper end with a hollow pendent arm p, within which is placed a shouldered spindle p², 20 carrying a roller p³, bearing upon the flat bar S of the carriage. Around the spindle is placed a coiled spring p⁴, the lower end of which bears upon the shoulder of the spindle and the upper end against the hollow 25 screw-plug p⁵, the function of which is to adjust the length of the projecting lower end of said spindle. The lever P is pivotally mounted at p' upon brackets projecting from the stationary bar B³. When the cam 30 Q, mounted on shaft C, presses against the end of said bent lever, it causes a downward pressure of the roller p³ upon the bar S of the carriage H during the inward stroke of the file, which is the cutting stroke, the side of 35 the saw being then well supported by the standard B of the frame. On the outward stroke of the file the carriage is slightly raised to free the saw from the file and to permit the feeding of the saw, and for this purpose a cam 40 R is so mounted upon the shaft C to bear against the under side of an arm s, pivoted to the standard B', which arm in turn lifts the bar S of the carriage and raises the latter and the file out of contact with the saw. It will 45 be apparent that the bar S, sliding on the standards B B', prevents the file from cutting deeper or at a different angle from what is intended. This entire action is performed at every revolution of the shaft E and for each 50 tooth of the saw operated upon.

It will be obvious to those skilled in the art to which the invention relates that modifications may be made in details without departing from the spirit and scope of the same.

55 Hence I do not limit myself to the precise construction and arrangement of parts hereinabove set forth and illustrated in the accompanying drawings; but,

Having described the nature and objects of the invention, what I claim as new, and desire to secure by Letters Patent, is—

1. The combination of the frame of the machine, the file-carrying carriage hinged thereto, said carriage having a slidable cylindrical rod and flat bar S lengthwise thereof and transverse arms uniting them, a shaft C parallel with the hinge-rod of said carriage, a cam upon said shaft, a pivoted angular lever having one end in engagement with said cam and in its other end a spring-pressed roller resting upon the bar S, and means for intermittently raising said bar S, substantially as described.

2. The combination of the frame of the machine, the file-carrying carriage hinged thereto, said carriage having a slidable cylindrical rod and flat bar S lengthwise thereof and transverse arms uniting them, a shaft C parallel with the hinge-rod of said carriage, a spring-pressed lever movable transversely of 75 said frame, a pawl-carrying lever operatively connected with said first-mentioned lever, a cam upon said shaft for advancing said first-named lever, and means for exerting pressure upon the bar S, and means for intermittently raising said bar S, substantially as described.

3. The combination of the frame of the machine, the file-carrying carriage hinged thereto having a slidable cylindrical hinge-rod and a flat bar S lengthwise thereof, a shaft C parallel with the hinge-rod, a cam upon said shaft, a pivoted lever resting upon said cam and adapted to bear against the under side of the bar S, and intermittently raise one side of the carriage, and means for depressing said 95 bar S, substantially as described.

4. The combination of the frame of the machine, the file-carrying carriage hinged thereto, a slidable cylindrical rod lengthwise of said carriage constituting the hinge-rod of said carriage, a vertical power-shaft, a wrist-pin, a connecting-rod, and a crank upon the vertical shaft to reciprocate the carriage, the horizontal main shaft, means for rotating said shaft, a saw-advancing pawl, means to carry 100 said pawl, a lever for operating the pawl-carrying means, a cam upon the horizontal shaft to advance said lever in one direction and a spring to retract it, substantially as described.

In testimony whereof I affix my signature 110 in presence of two witnesses.

ANDERS ANDERSSON.
